United States Patent Office

Des. 178,452
Patented Aug. 7, 1956

178,452

CHECK WRITER

Takayasu Inoue, Yokohama, Japan

Application March 3, 1955, Serial No. 34,850

Term of patent 14 years

(Cl. D64—11)

Fig. 1

Fig. 2

Des. 178,452

PAGE 2

Fig 3

Fig. 5

Fig. 4

Fig. 1 is a side elevational view of a check writer showing my new design;

Fig. 2 is a top plan view thereof.

Fig. 3 is another side elevational view thereof showing the side opposite to that of Fig. 1;

Fig. 4 is a rear view; and

Fig. 5 is a front view thereof.

I claim:

The ornamental design for a check writer, substantially as shown.
